UNITED STATES PATENT OFFICE.

HENRY WILDBERG, OF CINCINNATI, OHIO.

BOX AND CASE.

1,133,076.

Specification of Letters Patent.

Patented Mar. 23, 1915.

Application filed March 13, 1914. Serial No. 824,374.

To all whom it may concern:

Be it known that I, HENRY WILDBERG, a citizen of the United States, and a resident of the city of Cincinnati, in the county of Hamilton and State of Ohio, have invented certain new and useful Improvements in Boxes and Cases, of which the following is a full, clear, and exact description, reference being had to the accompanying drawings, forming part of this specification.

In the use of boxes and cases of a more or less permanent character such as for the transportation of bottle goods, where the case is used as a container by the purchaser and then returned to be used again by the seller, the life of the box is an important item. Not only does a rotting away or falling to pieces of the box cut short the usefulness and hence the value of the box, but in such case it is most liable to give way when it is filled with bottles or the like, thereby allowing the contents to drop out and probably break. In a beer case, for example, to illustrate the causes of decay or loosening of the box bottom, rubbish is liable to get into the bottom of such case. Beer from wet bottles will moisten this. The case is kept in a cool, damp place by preference, whereby moisture continually present on both the inside and outside of the box, gets an excellent opportunity to hasten decay. If left out in the weather, the box will catch rain water even though it has some drainage holes. All in all it is plain that in such a box, nail holes will soon rot out, nails partially oxidize and boards become loose, so that the case bottom may fall out at any time. It has been attempted to get away from this difficulty by nailing slats over the bottom of the box. This, however, is not successful, because slats easily pull out, and also because, while they do not retain the moisture like a solid bottom, yet they sit in moisture and catch enough at the joint with the sides to rot out the nail holes. Both slats and solid bottoms are equally liable to warp and pull away from the sides of a box.

It is the object of this invention to provide a bottomless box of the nature specified, and this is accomplished by that certain construction and arrangement of parts to be hereinafter specifically pointed out and claimed.

In the drawings, Figure 1 is a top plan view of the box. Fig. 2 is a vertical section thereof. Fig. 3 is a side elevation with part

of the side-board. Fig. 4 is an end elevation of the box. Fig. 5 is a perspective view of the same with one side wall removed, taken on a section along the lines 5, 5, of Fig. 4.

The box has sides 1, 1, and ends 2, 2, suitably nailed or dovetailed and glued together. The bottles 3, 3, are held in the box or case by segmentally grooved longitudinal partitions 4, 4. Recesses 5, 5, in the end boards of the box are formed to open at the bottom so that the partitions 4, 4, will slide into place from beneath. Nails 6, 6, are then employed to hold the partitions in place. These nails, it will be noted, are driven in away from the bottom of the box and not subjected to the rotting or rusting conditions of nails placed on the bottom. The ends 7, 7, of the partitions fit snugly into the recesses, and swelling owing to moisture will tend to tighten them in place. The partitions must be of a proper thickness to allow a series of segmental recesses 8 to be cut in them, back to back on each side of the partitions. These recesses are open at the top of the partitions and end before the bottom is reached, leaving a segmental shelf or ledge 9, integral with the partition. The partitions are spaced apart from each other and from the sides of the case, so that a bottle of the desired size will fit the space left between two adjacent recesses or between a recess and the side wall.

It can be seen that this box has no bottom whatever, supporting the bottles as it does on ledges formed integral with the partitions. There is no necessity for nailing any piece onto the bottom edge of the sides of this box, all nails being inserted above the danger point.

Having thus described my invention, what I claim as new and desire to secure by Letters Patent, is:—

1. In a container for bottles and the like, sides and ends for the container and a series of parallel partitions therefor, partially cut away so as to form recesses in the partitions and form ledges at the bottom of the recesses whereby the bottom and sides of the bottle are retained.

2. In a container for bottles and the like, sides and ends for the container, partitions therefor, partially cut away so as to form segmental shaped recesses in the partitions and ledges in said partitions at the bottom of the recesses.

3. In a container for bottles and the like,

5 sides and ends for the container, partitions therefor, partially cut away so as to form recesses in the partitions, and ledges integral with the partitions at the bottom of the recesses whereby the bottom and sides of the bottle are retained.

10 4. In a container for bottles and the like, sides and ends for the container, partitions therefor, partially cut away so as to form segmental shaped recesses in the partitions and ledges integral with the partitions at the bottom of the recesses whereby the bottom and sides of the bottle are retained.

15 5. In a container for bottles and the like, sides and ends for the container, partitions therefor, partially cut away so as to form recesses in the partitions located on each side thereof so as to present a series of ad-

jacent pockets between the partitions to engage opposite sides of bottles inserted in them and ledges in the partitions at the bottom of each recess. 26

6. In a container for bottles and the like, sides and ends for the container, partitions therefor, partially cut away so as to form segmental shaped recesses in the partitions located on each side thereof so as to present a series of adjacent pockets between the partitions to engage opposite sides of bottles inserted in them and ledges in the partitions 25 30 at the bottom of each recess.

HENRY WILDBERG.
